UNITED STATES PATENT OFFICE.

WILM KNOX, OF CLEVELAND, OHIO, ASSIGNOR TO THE CLEVELAND WIRE SPRING COMPANY, OF SAME PLACE.

DESIGN FOR A WALL-TIE.

SPECIFICATION forming part of Design No. 27,643, dated September 14, 1897.

Application filed July 22, 1897. Serial No. 645,600. Term of patent 7 years.

To all whom it may concern:

Be it known that I, WILM KNOX, a citizen of the United States, residing in Cleveland, in the county of Cuyahoga and State of Ohio, 5 have invented and produced a new and original Design for Wall Ties or Binders, of which the following is a specification, reference being had to the accompanying drawings, showing a part thereof.

10 In the accompanying drawings, Figure 1 is a plan elevation of my new design in wall-ties, and Fig. 2 is an edge view thereof.

The leading feature of my design consists in the shape or outline of the tie when viewed 15 in both side and edge elevations.

In the drawings, 2 indicates a straight stem, and 4 oblong loops at right angles to the stem and with their middle opposite the said ends.

This design is further distinguished by having the stem and loops continuous on one side 20 and separate on the other side in the angle where the stem and sides of the loop meet, and, lastly, by the fact that all portions of the design lie within the same plane when viewed edgewise. 25

What I claim is—

The design for a wall-tie substantially as shown and described.

Witness my hand to the foregoing specification this 21st day of June, 1897.

WILM KNOX.

Witnesses:

H. T. FISHER,
R. B. MOSER.
